(57) **CLAIM**

The ornamental design for an industrial lighting module, as shown and described.

DESCRIPTION

FIG. 1 is a top left perspective view of an industrial lighting module in accordance with my invention;

FIG. 2 is a bottom right view thereof;

FIG. 3 is a top view thereof;

FIG. 4 is a bottom view thereof;

FIG. 5 is a front view thereof;

FIG. 6 is a back view thereof;

FIG. 7 is a left view thereof; and,

FIG. 8 is a right view thereof.

The broken lines in the drawings depict portions of the industrial lighting module that form no part of the claimed design.
